CATALYST CHAMBER

Richard L. Huntington, Norman, Okla., assignor
to Phillips Petroleum Company, a corporation
of Delaware

Application January 2, 1942, Serial No. 425,481

3 Claims. (Cl. 23—288)

This invention relates to an improved equipment for catalytic treatment of hydrocarbons, in which provision is made for improving the heat distribution through the catalyst and for facilitating removal of the exhausted catalytic material after use.

A primary object of this device is to provide for a uniform distribution of heat through a catalyst bed, thus avoiding an otherwise natural tendency for the catalyst to be rapidly deactivated near the central axis of the chamber because of the high concentration of heat usually imposed in that area.

Another important object is to insure a distribution of the flowing medium in such a manner that all of the catalyst material will be contacted and utilized in a substantially uniform degree.

A further object is to prevent channeling of the catalyst by distributing the flow of treated material uniformly over the cross-sectional area of the catalyst case.

A yet further object is to provide for closer control over the process in operation, through the combined effect of uniform degree of contact with and uniform temperature conditions across the catalyst bed.

It is also an object to prevent coking of the catalyst, which would result from excessive heating of the catalyst in localized areas.

In the event agglomeration of the catalyst should occur for any reason, it is an additional object to provide means for easy removal of the fused material.

All of these objects and advantages, as well as others, will be apparent from the disclosure which follows.

In the drawing, numeral 1 refers to a case or chamber in which the catalytic process is carried out. Contained in the case is a bed of porous catalytic material 2, which may be of any desired composition, and which substantially fills the case. An inlet 3 is provided at one end of the structure for admission of the material to be processed, as a mixture of hydrocarbon gases, for example. At the opposite end of the case is provided an outlet 4 for withdrawal of the resultant product. Suitable flanges 5 and 6 are provided on the case for attachment of the inlet and outlet pipes by means of the companion flanges 7 and 8, to which the aforesaid pipes are secured by pipe threads, by welding, or other means.

Contained in the case and imbedded in the catalyst, is an inserted heat and flow distributor

welded or otherwise secured to the rigid shaft 9, and shown as a helical plate 10. Supporting ledges 11 and 12 are formed in the wall of the case 1, and the circular plates 13 and 14, respectively, rest thereon. These plates are extensively perforated or may have large sections cut out so that the resultant structure may resemble a spoked wheel. At the center of the plate or wheel 13 a boss 15 is provided with its central portion bored out to receive and provide a bearing for the shaft 9. The structure 14 is identical with that of member 13, with the exception that the bottom end of shaft 9 is machined to a reduced section 16 so that the surface 9A will serve as a thrust bearing to support the weight of the insert assembly composed of members 9 and 10. Therefore, the bore through the boss 17 will be smaller than that in the boss 15. The outside diameter of 14 will be slightly less than that of member 13 to permit insertion from above.

The upper end of shaft 9 is fitted with a square shank 18, which may be machined from the shaft stock. This shank is for the purpose of driving the shaft from some portable source of power 25 from the outside when the catalytic unit is shut down for cleaning out and replacement of the catalyst. The shank can be made accessible at such a time by removal of the flange 7 and the attached inlet pipe 3.

30 A screen 19 is provided to prevent the catalyst from passing into the outlet 4. Supporting and reinforcing members 20 are provided under the screen. These reinforcing members may simply be a series of structural angles, welded into the case at appropriate spacings to form a grid-like structure.

In operation, the catalyst case is prepared and utilized in the following manner.

40 The plate or bearing support 14 is lowered into place on the ledge 12. Next the helix 10 is lowered in place, the lower end of the shaft 9 being placed in the bearing or boss 17. The upper bearing support 13 is next lowered over the upper end of the shaft and comes to rest on the ledge 45 11. Catalyst is now poured in the top of the case and slides down the surface of the helical plate until filled to the desired level. The flange 7 with its feed pipe 3 attached is now bolted in place against the corresponding flange 5. The lower flanges 6 and 8 will only be used occasionally, as upon initial installation and when renewing the screen 19, or during other repair operations.

Having prepared the unit for use, preheated 55 gas or other material may now be fed through

the system in accordance with the requirements of the particular process undertaken. Gases or other media entering at high temperature from the feed line 3 will be caused to follow a spirally devious path through the catalyst bed. Due to the nature of the path so defined, contact with the catalyst will be widespread throughout the catalyst bed. Heat transfer from the flowing material to the catalyst will, therefore, be uniform, and excessive temperatures in localized areas will be avoided. This means that the catalyst will be deactivated uniformly and will thus give maximum benefits per unit of volume.

Upon continued running, there will come a time when the catalyst will become exhausted, at which time it will be necessary to shut down the unit and replace the worn out catalyst with new material. The flow of gas or other material having first been shut off at the source, the flange 7 is next removed. If the old catalyst in the case has become agglomerated for any reason, power may now be applied through the square shank 18 to rotate the helix and break loose any fused material, continued rotation forcing the material out of the top of the chamber. The helix may now be withdrawn through the top of the case bringing the catalyst material with it. Thus the removal of the worn out material is facilitated.

It is to be understood that the drawing which is a part of this specification shows a preferred form of my invention, but that many variations from this embodiment are possible within the scope of its teachings. My invention lies in the broad idea of uniformly distributing the flow through a catalyst chamber in order to obtain maximum contact of the medium with the catalyst, at the same time obtaining a uniform radial temperature distribution by means of an inserted helicoid member, and in providing easy means for breaking the member loose from the case to facilitate removal of the catalyst when desired. The details of construction are subject to many obvious variations in the matter of helical pitch, fabrication of the helix and its bearing supports, and others.

Having fully disclosed one practical form of my invention, I claim:

1. A stationary apparatus for catalytically treating hydrocarbons comprising an elongated stationary container filled with granular catalytic material, a normally stationary helical plate

within said container and surrounded by the catalytic material, said helical plate being of a diameter to just fit snugly within the container whereby the hydrocarbon fluids flow through the entire body of the catalyst in substantially a helical path, and said helical plate being rotatable for forced turning relative to the container to break up catalytic material and removable from the container to remove the catalytic material therefrom when spent, and a screen at one end of the helical plate through which the catalyst material cannot pass.

2. A catalyst chamber comprising in combination a body member having a bore therethrough, the bore being successively reduced in internal diameter to form two longitudinally spaced internal annular shoulders, a perforated end plate having a diameter intermediate the respective diameters of the annular shoulders to rest on the smaller diameter shoulder, a second perforated end plate of greater diameter than the internal diameter of the larger shoulder to rest thereon, a helical screw baffle extending between the two plates and fitting the bore therebetween, the end plates and baffle forming at least one helical chamber for reception of a granular catalyst, one end of the helical baffle extending through one of the end plates, means on said end for rotary driving engagement whereby the helical baffle plate may be forcibly rotated when removing the catalyst which may fuse and require breaking loose, and a screen adjacent one of said perforated plates through which the granular catalyst cannot pass.

3. A catalyst chamber comprising a body having a bore, an inlet and an outlet, perforated end plates extending across the bore and spaced longitudinally along the axis of the bore, a helical screw baffle extending between the two plates and fitting the bore therebetween, the end plates and baffle forming at least one helical chamber for reception of a granular catalyst, one end of the helical baffle extending through one of the end plates, means on said end for rotary driving engagement whereby the helical baffle plate may be forcibly rotated when removing the catalyst which may fuse and require breaking loose, and a screen adjacent the plate near the outlet through which the granular catalyst cannot pass.

RICHARD L. HUNTINGTON.
